DESIGN FOR A LAUNDRY BAG STAND

Charles A. Chidsey, Jr., Detroit, Mich.

Application September 12, 1941, Serial No. 103,324

Term of patent 14 years

To all whom it may concern:

Be it known that I, Charles A. Chidsey, Jr., a citizen of the United States, residing at Detroit, in the county of Wayne and State of Michigan, have invented a new, original, and ornamental Design for a Laundry Bag Stand, of which the following is a specification, reference being had to the accompanying drawing, forming a part thereof, in which:

Fig. 1 is a view in perspective of a laundry bag stand, showing my new design; and

Fig. 2 is an enlarged detailed sectional view taken on the line 2—2 of Fig. 1.

I claim:

The ornamental design of a laundry bag stand, substantially as shown.
